* cited by examiner

(72) Inventor: **Xiaobing Lei**, Chongqing (CN)

Primary Examiner — Anhdao Doan

(73) Assignee: **Chongqing Peninsula Medical Technology Co., Ltd.**, Chongqing (CN)

(74) *Attorney, Agent, or Firm* — Syncoda LLC; Feng Ma; Junjie Feng

(**) Term: **15 Years**

CLAIM

(21) Appl. No.: **29/549,597**

The ornamental design for a radiofrequency and ultrasound treatment apparatus, substantially as shown and described.

(22) Filed: **Dec. 27, 2015**

DESCRIPTION

(51) LOC (10) Cl. **24-01**

The patent or application file contains at least one drawing executed in color. Copies of this patent or patent application publication with color drawing(s) will be provided by the Office upon request and payment of the necessary fee.

(52) U.S. Cl.

USPC **D24/158**

(58) **Field of Classification Search**

USPC D24/158-161, 185, 186, 107, 209;

D28/9

CPC ... A61B 6/4405; A61B 6/4411; A61B 6/4435;

A61B 6/4441; A61B 6/4447; A61B

8/4405; A61B 8/4411; A61B 8/4427;

A61B 8/462; A61B 8/0437; A61B 8/0883

See application file for complete search history.

FIG. 1 is a front view of a radiofrequency and ultrasound treatment apparatus according to one embodiment of the disclosure;

FIG. 2 is a rear view of the radiofrequency and ultrasound treatment apparatus;

FIG. 3 is a left side view of the radiofrequency and ultrasound treatment apparatus;

FIG. 4 is a right side view of the radiofrequency and ultrasound treatment apparatus;

FIG. 5 is a top view of the radiofrequency and ultrasound treatment apparatus; and,

FIG. 6 is a bottom view of the radiofrequency and ultrasound treatment apparatus.
